UNITED STATES PATENT OFFICE

103,933

DESIGN FOR A STANDING LAMP

August Hendrich, Franklin, Ind., assignor to Charlie Hendrich, Bainbridge, Ind.

Application January 28, 1937, Serial No. 67,320

Term of patent 7 years

To all whom it may concern:

Be it known that I, August Hendrich, a citizen of the United States and resident of Franklin, county of Johnson, and State of Indiana, have invented a new, original, and ornamental Design for a Standing Lamp, of which the following is a specification, reference being had to the accompanying drawing, forming part thereof.

The figure is a perspective view of a standing lamp, showing my new design.

I claim:

The ornamental design for a standing lamp, as shown.

AUGUST HENDRICH.
